VALVE

William L. Huntington, Minneapolis, and Melvin G. Sogge, St. Paul, Minn., assignors to Minneapolis-Honeywell Regulator Company, Minneapolis, Minn., a corporation of Delaware

Application October 17, 1949, Serial No. 121,847

13 Claims. (Cl. 137—66)

1

This invention relates to safety valves generally and, more particularly, to improvements in safety valves for use in gas furnace installations to provide for the shutting off of gas to both the main burner and the pilot burner whenever the pilot burner flame has become extinguished.

Safety valves of this type are well known in the gas heating art. Some of the well known valves utilize the principle of a temperature responsive member, such as a rod and tube or a bimetallic member for latching or holding the main and pilot valves of the safety valve in their open positions, as long as a flame is present at the pilot burner, but moving to a position which permits said valve to close when said flame becomes extinguished. Others make use of a thermocouple energized electromagnet for holding the main and pilot valves in their open positions, due to the presence of a flame at the pilot burner which is positioned to heat the thermocouple, but which releases the valves to their closed positions upon the pilot burner flame becoming extinguished and thus deenergizing the electromagnet.

The present invention is primarily concerned with the last mentioned type of safety valve, that is, a thermocouple controlled main and pilot valve responsive to the presence or absence of a pilot burner flame.

An object of the invention is to provide a safety shut-off valve of the type described which is of reliable construction.

Another object of the invention is to provide a low cost safety valve having main and pilot valves therein, both of which are held in their open position by means of a thermocouple energizable electromagnet.

Still another object of the invention is to provide a main and pilot burner control valve which is manually resettable by a simple but sturdy mechanism to initiate gas flow to the pilot burner and then, if a flame is present at the pilot burner, to initiate and maintain gas flow to the main burner.

Still another object of the invention is to provide a safety valve providing a straight through gas passage therein and wherein the guides for the valves therein are formed in a single plate clamped between main body portions of the safety valve.

Still other objects of the invention will become apparent upon reading the following detailed description of the invention in conjunction with the accompanying drawings wherein:

Figure 1 is a vertical sectional view on the longitudinal axis of the safety valve;

2 Figure 2 is a sectional view taken along the line 2—2 of Figure 1;

Figure 3 is a sectional view taken along the line 3—3 of Figure 1; and

5 Figure 4 is a plan view of the safety valve with portions thereof broken away.

The valve body is formed of a lower casting 11 and an upper casting 12 clamped together by means of bolts 13 extending through holes in the upper casting 12 and into threaded holes 14 in the lower casting 11. A ring-like gasket 15, positioned within a groove 16 in the casting 12, provides a gas tight seal between the upper and lower castings.

15 The lower casting 11 has a main gas outlet 17 which is screw threaded to receive the end of a conduit leading to a main burner. It also has a laterally spaced smaller outlet 18 adapted to receive the end of a conduit leading to a pilot burner. The inner end of the outlet 17 is machined at 19 to form a valve seat for the main gas valve 20, to be presently described. The inner end of the outlet 18 is in communication with a recess 21, the upper end of which is machined to provide a valve seat 22 for the pilot valve 23, to be presently described.

20 Clamped in recesses in the inner edges of the castings 11 and 12 is a plate 24 having gas flow passages 25, 26 and 27 therein (see Figure 4). The plate also has bores 28 and 29 in axial alignment with the outlet 17 and recess 21, respectively, to receive the stems of the main and pilot valves, respectively. Welded to the upper surface of the plate, as seen in Figure 1, is a U-shaped bracket member 30 having a bore 31 therein in axial alignment with the bore 28, to also receive the stem of the main valve.

25 The main valve 20 is a dish-shaped rubber or plastic member having an annular depending rib 20a and an inwardly extending flange 20b which engages the upper surface of a washer-like disc 32. The disc, which is held on a stem 33 by means of a well known split washer fitted into an annular groove in the stem 33, serves as a stiffening means for the valve 20 and as a connecting means for said valve with the valve stem 33. As indicated above, the stem 33 is held in axial alignment with the outlet 17 and is vertically slidable in the bores 28 and 31. A centrally apertured cup shaped member 34 bears at its upper surface against the bottom of an enlarged shoulder portion 35 on the valve stem 33. It is held against this shoulder portion 35 by means of a split washer 36 positioned in an angular groove in the stem 33. A 30 second inverted and centrally apertured cup-

shaped member 37 surrounds the stem 33 and bears against the under surface of the plate 24. A spring 38 is held coaxial with the stem 33 by the sidewalls of the cup-shaped members 34 and 37, against the bottoms of which the ends of the spring bear. It is thus seen that the spring 38 normally holds the downwardly depending rib 20a of the valve head in seated engagement with the valve seat 19. To provide for vertical movement and opening of the main valve, an annular groove 39 is provided in the stem 33 to receive the forked end of an actuating means, to be presently described.

The above mentioned pilot valve 23 is secured to a valve stem 40 by being clamped to said stem between a washer 41 and an inverted and apertured cup-shaped member 42 positioned against an annular shoulder on said stem. A lower end of the stem is screw-threaded into a hexagonal extension member 40a which is vertically slidable in a recess 21a formed in the bottom of recess 21. This construction prevents a piston action of the extension 40a in guide recess 21a. The upper portion of the valve stem 40 passes through the bore 29 in the plate 24 for guiding the vertical movement of the stem.

Pivotedly mounted on the pilot valve stem 40 by means of a pivot 43 is a channel-shaped lever 44 having a forked end thereof extending transversely of the main valve stem 33 in the annular groove 39 therein. It is thus seen that vertical movement of the forked end 45 of the lever 44 will cause the lifting of the valve 20 off of its valve seat to provide for the flow of gas through the outlet 17. The right-hand end of the lever 44, as seen in Figures 1 and 3, is of open frame construction to permit the passage of the valve stem 40 therethrough between the side walls thereof. The side walls are vertically slotted at 46 to receive the pivot 43 and permit relative vertical movement between said pivot and the lever, for a purpose to be more fully understood hereinafter. The slot 46 is so positioned that the pivot 43 rests intermediate the ends thereof when the main valve 20 is seated and the right hand end of the lever 44 rests on a shoulder 47 formed on the inner wall of the lower casting 11. Two generally Z-shaped members 48 and 49 are welded or otherwise secured to the plate 24 on opposite sides of the valve stem 40 with the lower portions thereof extending transversely substantially to the right hand end of the lever 44, but spaced downwardly therefrom. A pair of tension springs 50 and 51, having screw threaded lower end portions and hook-shaped upper end portions, are adjustably secured to the lower portions of the legs 48 and 49, respectively, by adjusting screws 52 and 53, respectively. The upper hook-shaped portions of the springs 50 and 51 are adapted to engage in annular grooves in a cross bar 54 extending transversely through and beyond the side walls of the lever 44. The point at which the cross bar passes through the lever 44 is such that springs 50 and 51 tend to rotate the lever 44 about the abutment shoulder 47 as it pivots to urge the main valve 20 closed, aside from the action of the spring 38. Also, the springs 50 and 51 hold the lever 44 firmly in its lowermost position so that a light generally U-shaped spring 55, anchored to the lever 44 at its base with the free ends or the legs thereof extending downwardly in angular grooves near the ends of the pivot 43, cause the valve 23 to firmly engage the valve seat 22. The spring 55 is anchored to the lever 44 by having the face of the U-shaped spring cross the top of

the lever 44 with a looped portion of the legs of the U-shaped spring encircling the cross bar 54.

Manual means for actuating the valves to their operating positions comprises a crank member 56 having a crank arm 57 adapted to engage a horizontally extending arm 44a on the lever 44 as the crank member 56 is rotated through an angle of 90°. Further rotation of the crank member will cause the lifting of the arm 44a and the lever 44, with the consequent lifting of the pilot valve 23. The rotation of the crank member 56 is accomplished by rotating a manually engageable knob 58 externally connected to a shaft 59 which in turn is connected to the crank member 56. A rubber washer 60 having an inner diameter smaller than the diameter of the stem 59, is held in place in a recess in the outer surface of the casting 11 by means of a tightly fitting metallic washer 61 to form a gastight seal between the casting 11 and the stem 59. A pointer 58a is provided on the knob to cooperate with a plate 62 carrying indicia to indicate the position of the crank arm 57 at all times. The knob 58 is held on the crank shaft or stem 59 by means of a lock washer 63 and screw 64. The indicia plate 62 has a flat upper portion which bears against a flat shoulder on the lower casting 11 to prevent rotation thereof and is held against the end of the lower casting by means of a washer 65 and a well known clip spring 66 engaging an angular groove in shaft 59 adjacent the washer 65.

The means for holding the pilot valve 23 in its open position is an electromagnet having a U-shaped core member 67 centrally apertured in its base portion to receive a stud 68. The stud is staked to hold the core 67 on the inner wall of the casting 12. Mounted on one of the legs of the core 67 is a conventional low voltage coil 69 which is adapted to be energized by a thermocouple. Leads 70 from the ends of the coil are connected to the inner ends of electrical terminal screws 71 extending through a terminal block 72 made of insulating material. The terminal block 72 is secured to the upper casting 12 with a sealing gasket 73 therebetween, by means of bolts 74 freely passing through the terminal block and screw-threaded into suitable aligned and threaded bores (not shown) in the castings 12. The coil 69 is resiliently but firmly held on the core and against the lower end of the stud 68 by means of a U-shaped leaf spring 75, the center portion of which bears against the coil while the ends thereof bear against the plate 24. The core 67 is prevented from rotating on the stud 68 by means of ribs 76 formed on the inner surface of the casting 12. An armature 77, mentioned above as being secured to the upper end of stem 40, abuts a shoulder on said stem and is held thereon by means of a conventional clip 78 fitting in an annular groove in the stem. The electromagnet and armature are separated from the inlet 12a and the other gas passages by a partition wall 12b, formed in the upper casting 12, and by the plate 24 which bears against it. While this junction of the wall 12b with plate 24 is preferably a gastight one, it is not absolutely necessary that such be the case.

Operation

The elements of the safety valve are shown in Figure 1 as being in the positions they would have in a shut down condition of a heating system of the type mentioned above. To initiate the flow of gas to the pilot, so that it may be lighted, knob 58 is rotated clockwise to bring

the crank arm 57 into engagement with lever arm 44a. Continued clockwise movement of the knob will cause upward movement of the right hand end of the lever 44, about the groove 39 in the main valve stem as a pivot, to raise the 5 lever 44 against the pivot 43 and thus move the pilot valve to its open position, with the armature 77 in engagement with the electromagnet core 67. The knob must be held in this last mentioned position for a sufficient time for the pilot burner to heat the thermocouple to the extent necessary for said thermocouple to supply sufficient electrical current to the electromagnet. The current will pass through the electrical terminals 71 to hold the armature 77 in engagement with the electromagnet against the bias of springs 50 and 51, and 38, when the knob 58 has been rotated counterclockwise to its starting position. Should the armature 77 be held by the electromagnet, indicating that the pilot 20 flame is of necessary intensity, as well as being present, the springs 50 and 51 which are much stronger than the spring 38 will rotate lever 44 about pivot 43 to raise the main valve 20 off of its seat against the bias of spring 38. The valve 25 elements will remain in their positions so long as the pilot burner remains lighted and is of the desired intensity.

Should the pilot flame become extinguished or lower in intensity to the point wherein it does 30 not provide a flame suitable for igniting gas at the main burner, and thus become insufficient to heat the thermocouple to the temperature necessary to deliver sufficient current to the electromagnet, springs 50, 51, 55 and 38 will cause the main and pilot valves to close. It is thus seen that the main valve cannot be opened by the manual reset means unless there is a sufficient flame present at the pilot burner to cause the armature 77 to be held by the electromagnet. This provides safe ignition of the heating system at the beginning of the heating season or after a safety shutdown of the system.

While the preferred construction of the invention has been described above, it is obvious that 45 modifications may be made therein without departing from the spirit of the invention. The scope of the invention should therefore be determined solely from the appended claims.

We claim as our invention:

1. A device of the class described, comprising a main biased-closed valve controlling fluid flow through a main outlet, a secondary valve controlling fluid flow through a secondary outlet, an inlet common to both of said valves, means responsive to a condition for holding said secondary valve in its open position when a predetermined condition exists, an actuating lever for said valves having one end thereof engaging said main valve, a lost motion connection between said secondary valve and an intermediate portion of said lever, biasing means between said lever and said secondary valve for urging said secondary valve toward its closed position, an abutment engageable by the other end of said lever, biasing means engaging said lever between said secondary valve and said other end of said lever with a force greater than the closing bias lever on said main valve for urging said lever in a direction closing said valves when said secondary valve is closed and for opening said main valve against its bias when the condition responsive means is holding said secondary valve open, and means positioned to engage said other end of said lever for moving said secondary valve to its 75

open position and into engagement with said holding means.

2. A device of the class described, comprising a main biased-closed valve controlling fluid flow through a main outlet, a secondary valve controlling fluid flow through a secondary outlet, an inlet common to both of said valves, means responsive to a condition for holding said secondary valve in its open position when a predetermined condition exists, an actuating lever for said valves having one end thereof engaging said main valve, a pivotal connection between said secondary valve and an intermediate portion of said lever, biasing means engaging said lever between said secondary valve and said other end of said lever with a force greater than the bias on said main valve for urging said lever in a direction closing said secondary valve and for opening said main valve against its bias when said condition responsive means is holding said secondary valve open, and means positioned to engage said other end of said lever for moving said secondary valve to its open position and into engagement with said holding means.

3. A device of the class described, comprising a main valve controlling fluid flow through a main outlet, a secondary valve controlling fluid flow through a secondary outlet, an inlet common to both of said valves, means responsive to a condition for holding said secondary valve in its open position when a predetermined condition exists, an actuating lever for said valves having one end thereof pivotally engaging said main valve, a pivotal connection between said secondary valve and an intermediate portion of said lever, an abutment engageable by the other end of said lever, biasing means engaging said lever between said secondary valve and said other end of said lever for urging said lever in a direction closing said valves and for pivoting said lever about said connection to open said main valve when said secondary valve is held by said holding means, and means positioned to engage said other end of said lever for moving said secondary valve to its open position and into engagement with said holding means.

4. A device of the class described, comprising a main biased-closed valve controlling fluid flow through a main outlet, a secondary valve controlling fluid flow through a secondary outlet, an inlet common to both of said valves, means responsive to a condition for holding said secondary valve in its open position when a predetermined condition exists, said means comprising an armature connected to said secondary valve and an electromagnet, an actuating lever for said valves having one end thereof engaging said main valve, a pivotal connection between said secondary valve and an intermediate portion of said lever, an abutment engageable by the other end of said lever, biasing means engaging said lever between said secondary valve and said other end of said lever with a force greater than the bias on said main valve for urging said lever in a direction closing said valves and for opening said main valve against its bias when said condition responsive means is holding said secondary valve open, and means positioned to engage said other end of said lever for moving said secondary valve to its open position and into engagement with said holding means, said last mentioned means comprising a crank having a rotatable shaft the axis of which is substantially parallel to the longitudinal axis of said actuating lever.

5. A device of the class described, comprising a main valve controlling fluid flow through a main outlet, a secondary valve controlling fluid flow through a secondary outlet, an inlet common to both of said valves, means responsive to a condition for holding said secondary valve in its open position when a predetermined condition exists, said means comprising an armature connected to said secondary valve and an electromagnet, an actuating lever for said valves having one end thereof pivotally engaging said main valve, a pivotal connection between said secondary valve and an intermediate portion of said lever, an abutment engageable by the other end of said lever, biasing means engaging said lever between said secondary valve and said other end of said lever for urging said lever in a direction closing said valves and for pivoting said lever about said connection to open said main valve when said secondary valve is held by said holding means, and means positioned to engage said other end of said lever for moving said secondary valve to its open position and into engagement with said holding means.

6. A safety shut-off valve comprising a valve body having an inlet and first and second outlets, a first valve for said first outlet, a second valve for said second outlet, an abutment in said valve body, a lever pivotally engaging said first valve at one of its ends and resting on said abutment at the other end thereof, said lever having a lost motion connection intermediate its ends with said second valve, condition responsive means for holding said second valve in its open position, means acting on said lever inwardly of said other end of said lever for moving said lever in a direction tending to close said valves when said lever is resting on said abutment and for rocking said lever about said lost motion connection to open said first valve when said condition responsive means is holding said second valve, and means for lifting said other end of said lever off of said abutment to move said second valve to its open position.

7. A safety shut-off device comprising a valve body having an inlet and first and second outlets, a first valve for said first outlet, a second valve for said second outlet, a lever pivotally engaging said first valve at one of its ends and having a pivotal connection intermediate its ends with said second valve, releasable means for holding said second valve in its open position, means acting on said lever inwardly of the other end of said lever for moving said lever in a direction tending to close said second valve and for rocking said lever about said pivotal connection to open said first valve when said releasable means is holding said second valve, and manually operable means for lifting said other end of said lever to move said second valve to its open position.

8. A safety shut-off valve comprising a valve body having an inlet and first and second outlets, a first valve for said first outlet, a second valve for said second outlet, an abutment in said valve body, a lever pivotally engaging said first valve at one of its ends and resting on said abutment at the other end thereof, said lever having a pivotal connection intermediate its ends with said second valve, releasable means for holding said second valve in its open position, means between said second valve and said lever for urging said second valve toward its closed position and away from said lever, means acting on said lever inwardly of said other end of

said lever for moving said lever in a direction tending to close said valves when said lever is resting on said abutment and for rocking said lever about said pivotal connection to open said first valve when said releasable means is holding said second valve, and manually operable means for lifting said other end of said lever off of said abutment to move said second valve to its open position.

10. 9. A safety shut-off valve comprising a valve body having two generally cup-shaped portions joined together, an inlet in one of said portions, a first outlet in the other of said portions in axial alignment with said inlet, a plate clamped between said portions having openings in alignment with said inlet and outlet, a biased closed main valve cooperating with said outlet and having a stem extending through one of said openings in said plate for guiding said valve with respect to said outlet, a second outlet laterally spaced from said first outlet, a second valve cooperating with said second outlet and having a stem extending through an opening in said plate, an armature secured to said second valve stem on the opposite side of said plate from said second valve, an electromagnet positioned to be engaged by said armature when said second valve is in its open position, a lever pivotally engaging the main valve stem at one end thereof and the second valve stem intermediate its ends, means biasing the other end of said lever in a direction tending to close said second valve, and manually operable means for lifting said other end to open said second valve and to position said armature against said electromagnet, said biasing means being operable upon return movement of said manually operable means to move said main valve to open position if said electromagnet is energized.

40 10. A safety shut-off valve as defined in claim 9 wherein said manually operable means comprises a rotatable shaft extending through said valve body substantially parallel to the longitudinal axis of said lever.

45 11. A safety device comprising a support, first means for controlling the flow of fuel to a first burner, second means for controlling the flow of fuel to a second burner, a lever pivotally engaged at one of its ends to said first means, said lever being pivoted intermediate its ends to said second means, means for releasably holding said second means in its position permitting fuel flow, first biasing means acting on said lever near the other end of said lever for moving said second means to its position stopping fuel flow when it is free to so move or for rocking said lever about its pivotal connection with said second means to move said first means to its position permitting fuel flow, second biasing means weaker than said first biasing means for moving said first means to its position stopping fuel flow, and means engaging said other end for moving said lever into engagement with said holding means.

65 12. A safety device comprising a support, first means for controlling the flow of fuel to a first burner, second means for controlling the flow of fuel to a second burner, a lever pivotally engaged at one of its ends to said first means, said lever being pivoted intermediate its ends to said second means, condition responsive means for releasably holding said second means in its position permitting fuel flow, first biasing means acting on said lever near the other end of said lever for moving said second means to its posi-

tion stopping fuel flow when it is free to so move or for rocking said lever about its pivoted connection with said second means to move said first means to its position permitting fuel flow when said condition responsive means is holding said second means, second biasing means weaker than said first biasing means for moving said first means to its position stopping fuel flow, and means engaging said other end for moving said lever into engagement with said holding means.

13. A safety device comprising a support, first means for controlling the flow of fuel to a first burner, second means for controlling the flow of fuel to a second burner, a first electromagnetic member connected to said second means, a lever 15 pivotally engaged at one of its ends to said first means, said lever being pivoted intermediate its ends to said second means, a second electromagnetic member cooperable with said first electromagnetic member for releasably holding said 20 second means in its position permitting fuel flow, first biasing means acting on said lever near the

other end of said lever for moving said second means to its position stopping fuel flow when it is free to so move or for rocking said lever about its pivoted connection with said second means to move said first means to its position permitting fuel flow, second biasing means weaker than said first biasing means for moving said first means to its position stopping fuel flow, and means engaging said other end for moving said lever into engagement with said holding means.
